VOLUME CONTROL FOR ELECTRICAL
SOUND REPRODUCER

Robert H. Dreisbach, Fort Wayne, Ind., assignor,
by mesne assignments, to The Magnavox Company,
Incorporated, Fort Wayne, Ind., a corporation of Indiana

Application November 30, 1936, Serial No. 113,445

8 Claims. (Cl. 179—1)

The present invention relates to volume control means for electrical sound reproducing apparatus and more particularly to a volume control having means which will compensate for the varying sensitivity of the human ear at different sound levels.

An object of the present invention is to provide a new, novel and efficient volume control means for electric sound reproducing apparatus such as 10 radio receivers, microphones and electrical phonographs.

Another object of the invention is to provide a volume control having a novel arrangement of resistance and capacitance to automatically compensate for the varying sensitivity of the human 15 ear at different sound levels.

Another object of the invention is to provide a compensating circuit for a volume control means which will provide a more uniform volume response at different frequencies and over a wider sound frequency range than has heretofore been possible.

Another object of the invention is to provide a variable volume control means for use with 25 electrical phonographs that will compensate for the inherent defect which results from the fact that the phonograph records are cut at a constant amplitude below frequencies of 400 cycles instead of at a constant velocity, as is the case at 30 the higher frequencies.

It is known that the sensitivity of the human ear varies throughout the entire frequency range and that the ear is more sensitive to changes in sound level at the lower and high sound frequencies. Therefore it is a further object of the 35 present invention to provide a suitable compensating means for use in connection with a volume control device which will automatically compensate for the changing sensitivity of the human ear at both the high and low sound levels.

Other objects and advantages of the invention will be in part pointed out and in part evident to those skilled in the art as the description thereof proceeds.

For a better understanding of the invention 45 reference should be had to the accompanying diagrams which will serve in connection with the description to illustrate one embodiment of the invention.

In the drawing:

Figure 1 shows a simple volume controlling device for use in connection with a piezo-crystal type of phonographic pick-up.

Figure 2 is a diagram similar to Figure 1, showing 55 a similar arrangement for a phonographic

pick-up having means adapted to compensate for deficiencies inherent in sound records.

Figure 3 is a modification of the circuit illustrated in Figure 2, showing an arrangement for rendering the compensating feature more effective as the volume of sound is decreased.

Figure 4 shows an arrangement similar to that of Figure 3, with an additional compensating means which is operative in the low frequency range when the volume control is operating at a 10 high sound level.

Figure 5 is a diagram showing an arrangement having all of the advantages possessed by the previously illustrated arrangements plus means operative at the higher sound frequencies when 15 the volume control is operating at a low sound level, and

Figure 6 is a chart graphically showing the effect of the volume control and compensating means at different sound levels.

It will be apparent that if all sound programs were reproduced at their original sound level the reproduced sound would effect the human ear in the same manner as would the sound at the original source, irrespective of the sensitivity characteristics of the human ear. However, since it is not always desirable and/or feasible to reproduce the sound program at its original sound level, it is customary to provide a volume control device which may be operated to either raise or 20 lower the sound level. Since the sensitivity of the human ear varies as the sound level is changed, it is desirable that means be provided with the volume control device to compensate for this change in sensitivity of the ear. This 25 characteristic of the human ear is particularly noticeable below a sound frequency of 400 cycles per second and above a sound frequency of approximately 2000 cycles per second. For example, at the relatively high sound level the human ear 30 is more sensitive to frequencies below 400 cycles per second and to frequencies above 2000 cycles per second than it is to the intermediate range of frequencies. Conversely at a low sound level the ear is less sensitive to sound frequencies below 400 35 cycles and to the sound frequencies above approximately 2000 cycles per second than it is to the intermediate range of frequencies. Consequently if the overall loudness of the reproduced program is considerably and uniformly increased, 40 to the observer the low and high frequency sounds will seem to have been increased out of proportion to the overall increase in loudness.

On the other hand, if the overall loudness of the reproduced music is considerably and uni- 45 50 55

formly decreased, to the observer the low and high frequency sounds will appear to have been decreased out of proportion to the overall decrease in loudness, and as a result the music in each of these instances will lack the fullness and richness characteristic of a normal reproduction over a wide frequency range.

In accordance with the present invention compensation is provided in connection with the volume control means which will automatically increase the relative intensity of the low and high frequency sounds, with respect to the sounds of the intermediate frequency, when the overall loudness of the reproduced program is decreased by the volume control means. At the same time the invention also provides a compensating arrangement which will automatically decrease the relative intensity of the low and high frequency sounds, with respect to the sounds of the intermediate frequency, when the overall loudness of the program is increased to a high level by means of the volume control means. The present invention also provides fixed compensation for imperfections in other parts of the sound reproducing equipment, and particularly those imperfections which occur in phonographically reproduced sound programs, wherein, as is well known, the sound records are customarily cut with constant amplitude for constant input at sound frequencies below approximately 400 cycles per second rather than at constant velocity, as is the case throughout the remaining sound frequency range. This method of cutting the sound records, unless compensated for, results in a relatively decreased response at the lower sound frequencies, and as a result the response below 400 cycles per second will be substantially proportional to the frequency.

In the remaining description it will be understood that where reference is made to the low frequency sounds, this will include those frequencies up to approximately 400 cycles per second, and that when the higher frequencies are referred to, this will include those frequencies above 2000 cycles per second. It will be also understood that when reference is made to compensation in either the normal, high or low sound levels, that the compensation made will be with respect to the level established by the intermediate frequency range as a reference point.

Reference is now made to the drawing for a progressive description of the invention with respect to the several figures thereof.

In Figure 1 of the drawing, there is shown a piezo-electric crystal voltage generating pick-up 10, for use in connection with a phonograph sound record. Connected to the pick-up 10 there is a volume controlling resistance R_1 , having a 55 slidable contact 11 cooperating therewith. The impedance of the resistance R_1 is high at low frequencies, as compared to the impedance of the crystal pick-up, in order that no attenuation of the low frequency voltages will occur.

Figure 2 of the drawing shows the arrangement of Figure 1, with an equalizing circuit, by means of which the higher frequencies are attenuated in such a manner that the overall electrical response from the pick-up 10 will be 65 relatively flat throughout the sound frequency range from 40 cycles to 8000 cycles when used with a phonograph record cut in accordance with present practice, wherein all frequencies below approximately 400 cycles are cut at a constant amplitude for a constant input to the record

cutter. This equalizing circuit includes a resistance R_2 , which is connected in series with a resistor R_3 and a capacitor C_1 to form a shunt circuit across the output of the crystal pick-up 10. In this arrangement the resistor R_1 with 5 its slidable contact 11 is connected at one side between the resistor R_2 and the capacitor C_1 , and will operate independently of the equalizing circuit to raise and lower the sound volume.

In Figure 3 of the drawing, the resistance R_3 10 and the capacitor C_1 are, as before, connected in series as a shunt across the pick-up 10, and the resistance R_2 is shown as provided with a slidable contact 12, by means of which its effective value in the shunt circuit may be varied 15 as the slidable contact 11 is moved along the resistance R_1 to vary the volume of sound. This is accomplished by controlling the slidable contacts 11 and 12 with a single operating knob 20 or other means, so that when the sound level is increased by an upward movement of the contact 11 along the resistance R_1 , the contact 12 will move to the left along resistance R_2 and gradually cut the resistance R_2 out of the circuit.

At frequencies above 400 cycles, or any other 25 chosen frequency, the impedance of the capacitor C_1 is low with respect to that of resistance R_3 , so that the combined impedance of this circuit will be substantially constant for currents from 400 cycles per second up to the highest frequencies encountered in the reproduced sound range. The value of resistance R_3 is low with respect to the value of the resistance R_2 , so that with all or a considerable portion of the resistor R_2 in the circuit, the capacitor C_1 and resistor 30 R_3 will shunt a considerable portion of the current, decreasing more or less uniformly the voltage of the sound current above 400 cycles per second. In this and the other arrangements the value of the capacitor C_1 is chosen so that 35 at frequencies below 400 cycles its impedance will become important with respect to that of R_3 , and consequently the lower the frequency the less will be the current which is shunted thereby, and the less the output voltage will be 40 reduced. The overall effect of the capacitor C_1 and resistor R_2 then, with the resistor R_3 in the 45 circuit, is to attenuate substantially uniformly all frequencies above 400 cycles, or some other chosen frequency, and below this frequency, to 50 attenuate less and less as the frequency is reduced. Considered with respect to the high frequencies at a given intensity level, the lower frequencies are raised in sound level, with the amount of raise in sound level increasing as the 55 frequency decreases. In other words, as the level is increased by means of the volume control, and the resistance R_2 is gradually cut out of the circuit, and the impedance of the pick-up alone, or in series with a small portion of the resistance 60 R_2 , becomes low with respect to the resistance R_3 , the reduction in voltage due to the shunt circuit $C_1 R_3$ becomes much less, and as a result the compensating effect described above will 65 become much less, although acting in the same general direction with respect to the sound frequency.

The adjustment of contact 11 upon the resistance R_1 , which is operated simultaneously with the contact 12 upon the resistance R_2 , does 70 not of itself change the compensation described above, but merely changes the voltage uniformly without respect to frequency, thus synchronizing the overall loudness control with the frequency compensation mentioned above.

The arrangement illustrated in Figure 4 of the drawing is similar to that shown in Figure 3, with an additional resistance R_4 , which provides compensation in the low frequency range when operating at a high sound level. In its operation resistance R_4 provides a low resistance load for the relatively high impedance of the pick-up at low frequencies, and thus tends to decrease the sound volume at the low sound frequencies. The resistance R_4 does not appreciably affect the variable frequency compensation described above, as long as the combined resistance of R_1 and R_4 , in partial shunt, is large with respect to the impedance of the shunt circuit, including the capacitor C_1 and the resistor R_3 . This is particularly true for loudness settings from a low to a maximum or rather high sound level. In volume control adjustments approaching maximum loudness, however, when the relatively low resistance R_4 parallels most or all of the resistance R_1 , the combined resistance of R_1 and R_4 is relatively low. At this setting the resistance R_2 will be largely or completely cut out of the circuit, and therefore the voltage at the lower frequencies will be relatively reduced, because the pick-up 10, which has a high impedance at low frequencies, will at these frequencies be feeding into an impedance which is low with respect to its own impedance, and also partly because the compensating effect of the shunt circuit, including the capacitor C_1 and the resistor R_3 , will be reduced due to the parallel low impedance circuit formed by the resistances R_1 and R_4 . The resistance R_4 will have substantially no direct effect upon the sound volume at low sound level settings, but will reduce the compensating effect of the resistance R_2 and the shunt circuit formed by capacitor C_1 and resistance R_3 at the high sound level settings.

The arrangement illustrated in Figure 5 is similar to that just described in connection with Figure 4, with an additional capacitor C_2 therein to provide additional compensation in the high frequency range when the volume control is operating at a low sound level. In this arrangement the capacitor C_2 will have little or no effect at the high volume or loudness settings, as it is at this time shunted across only a small portion of the resistor R_1 . At low volume settings, however, it will be shunted across a greater portion of the resistor R_1 , or a higher value of resistance. The capacity of the capacitor C_2 is so chosen that its impedance at high frequencies will be low with respect to that part of R_1 which it parallels, although its impedance at low frequencies will still be high with respect to that part of R_1 which it parallels. By thus providing a low impedance path for the high frequencies, the voltage at these frequencies is increased with respect to the voltage at the intermediate frequencies, and the amount of compensation is increased as the volume control is operated to lower the volume or loudness of the sound.

In Figure 6 of the drawing there is shown a series of curves which graphically illustrate the results obtained by the invention at different sound levels over a frequency range varying from approximately 31 cycles to 8000 cycles per second. In this figure of the drawing, the upper curves represent graphically the effect of loud sound reproduction upon the human ear, both with and without compensation as provided for by this invention at different frequencies, and the lower curve represents the effect upon the human ear, both with and without compensation, at a

low sound level of reproduction. The intermediate curves show the effect produced by the invention in compensating for the deficiency found in phonographic records below sound frequencies of approximately 400 cycles per second, 5 as well as compensation for the varying sensitivity of the ear at the extremes of the frequency range.

As shown in the upper curves, the compensation provided by the volume control means lowers the 10 volume of sound at the extreme ends of the sound frequency scale so that the intermediate range of frequencies will to all intents and purposes be reproduced at substantially the same level of volume as the low and high frequencies, whereas, 15 as illustrated in the lower series of curves, the volume control will function to increase the tonal response at the ends of the sound frequency range, so that the intermediate sound frequency range will to all intents and purposes be relatively 20 somewhat lower than the frequencies at the upper and lower ends of the frequency scale. In connection with the intermediate series of curves, the volume control serves particularly to elevate the volume of the lower frequency sounds and thus 25 compensate for the deficiencies found in phonograph records, as has been heretofore described. At this sound level the higher frequencies are also somewhat elevated so that in effect the sound, while produced at its original and normal 30 volume, will have more fullness and richness of tone throughout the entire frequency range.

It will be understood that the amount of compensation and the manner of variation provided with respect to frequency and with respect to 35 loudness levels can be adjusted over wide ranges by selecting different and proper values for the resistances R_1 , R_2 , R_3 and R_4 , and the capacitors C_1 and C_2 , and also by adjusting the coupling between the resistors R_1 and R_2 . 40

While I have, for the sake of clearness and in order to disclose the invention so that the same can be readily understood, described and illustrated specific devices and arrangements, I desire to have it understood that this invention is 45 not limited to the specific means disclosed, but may be embodied in other ways that will suggest themselves to persons skilled in the art. It is believed that this invention is new and it is desired to claim it so that all such changes as come 50 within the scope of the appended claims are to be considered as part of this invention.

Having thus described my invention, what I claim and desire to secure by Letters Patent is— 55

1. In a sound reproducing system of the character described, the combination of a phonographic pick-up device adapted to generate voltages of sound producing frequencies, a variable volume control resistance connected in shunt across the output of said pick-up device, the impedance of said volume control resistance being high as compared to that of the pick-up device, a second variable resistance in series with the output of said pick-up device, said variable volume control resistance and said second variable resistance being adjustable in unison, and a filter adapted to attenuate the voltages generated by said pick-up substantially uniformly at all frequencies above 400 cycles per second and in a diminishing manner as the frequency of the sound current decreases, said filter circuit including a capacitance and a resistance connected in shunt across said pick-up device and said second resistance and in parallel relation with said volume control resistance. 65 70 75

2. In a volume controlling system for electrically produced modulated currents of sound producing frequencies, the combination of a modulated current source, a resistance in series with said source of modulated current having a variable contact, a volume controlling resistance connected in shunt with said first resistance and said source of modulated current and also having a variable volume controlling contact associated therewith, the variable contacts of said first and second resistances being controllable in unison by a single operating means, a filter circuit including a capacitance and a resistance connected in shunt with said volume controlling resistance, a low resistance shunt connected between the adjustable contact and one side of said modulated current source to shunt a portion of said volume controlling resistance, and a capacitor connected between the adjustable contact upon said volume controlling resistance and the other side of said modulated current source to operate in shunt with a portion of said volume controlling resistance. 10
3. In a volume controlling system for electrically produced modulated currents of sound reproducing frequencies, the combination of a modulated current source, a volume controlling resistance connected in shunt with said source of modulated current and having a variable volume controlling contact associated therewith, a filter circuit including a capacitance and a resistance connected in shunt with said volume controlling resistance, a low resistance shunt connected between the adjustable contact of said volume controlling resistance and one side of said modulated current source to shunt a portion of said volume controlling resistance, and a capacitor connected to the adjustable contact of said volume controlling resistance and the other side of said modulated current source, whereby said low resistance and said capacitor will operate in shunt with varying portions of said volume controlling resistance as its slidable contact is moved thereover. 20
4. In a volume controlling system for electrically produced modulated currents of sound reproducing frequencies, the combination of a modulated current source, a variable resistance in series with said source of modulated current, a volume controlling resistance connected in shunt with a portion of said variable resistance and said source of modulated current and having a variable volume controlling contact associated therewith, a filter circuit including a capacitance and a resistance connected in shunt with said volume controlling resistance, a low resistance shunt connected between the adjustable contact and one side of said modulated current source to shunt a portion of said volume controlling resistance, a capacitor connected between the adjustable contact upon said volume controlling resistance and the other side of said modulated current source, whereby it will operate in shunt with a portion of said volume controlling resistance, and a means for simultaneously adjusting the value of said variable resistance and said volume controlling resistance. 30
5. In a volume controlling system for electrically produced modulated currents of sound reproducing frequencies, the combination of a source of modulated current having capacitive reactance, a volume controlling resistance connected in shunt with said source of modulated current and having an adjustable volume controlling tap associated therewith, a filter circuit including a capacitance and a resistance connected in shunting relation with said volume controlling resistance, and a low resistance shunt connected between the adjustable tap of said volume controlling resistance and one side of said modulated current source operating to shunt a portion of said volume controlling resistance, whereby said low resistance will operate in parallel with varying portions of said volume controlling resistance as its adjustable tap is moved thereover. 40
6. In a compensated volume controlling system for the attenuation of modulated sound currents to produce a uniform level of response over a wide range of frequencies, the combination of a modulated current input source having capacitive reactance, a volume controlling resistance connected in shunt across said input source and having a variable output control contact associated therewith, the total resistance of said volume controlling resistance being high as compared to the impedance of the capacitive input source at low frequencies to avoid attenuation at the low frequencies, and a low resistance shunt connected to parallel with varying portions of said volume controlling resistance as determined by the adjustment of its variable output control contact, whereby the effective value of said volume controlling resistance will be decreased at the higher sound volumes. 50
7. In a compensated volume controlling system for the attenuation of modulated sound currents to produce a uniform response over a wide range of frequencies, the combination of a sound record having a uniform amplitude of cutting, a crystal pick-up device cooperating with said sound record and having capacitive reactance, a volume controlling resistance connected in shunt across said pick-up device having a variable output control contact associated therewith, the total resistance of said volume controlling resistance being high as compared to the impedance of said crystal pick-up device at low frequencies to avoid attenuation at the low frequencies, and a low resistance shunt connected to parallel with varying portions of said volume controlling resistance as determined by the adjustment of its variable output control contact, whereby the effective value of said volume controlling resistance will be decreased at the higher sound volumes. 60
8. In a compensated volume controlling system for the attenuation of modulated sound currents to produce a uniform level of response over a wide range of frequencies, the combination of a modulated current input source having capacitive reactance, a volume controlling resistance connected in shunt across said input source and having a variable output control contact associated therewith, the total resistance of said volume controlling resistance being high as compared to the impedance of the capacitive input source at low frequencies to avoid attenuation at the low frequencies, a low resistance shunt connected in parallel with varying portions of said volume controlling resistance as determined by the adjustment of its variable output control contact, and a capacitance connected in series with said low resistance shunt and operating in parallel with the remaining portion of said volume control resistance as determined by the adjustment of its variable output control contact. 70
